UNITED STATES PATENT OFFICE.

JAMES NEULIN BROWN, OF DES MOINES, IOWA, ASSIGNOR OF ONE-HALF TO JOHN C. LITTLE, OF DES MOINES, IOWA.

LATCH.

1,415,786.

Specification of Letters Patent. Patented May 9, 1922.

Application filed April 13, 1921. Serial No. 460,906.

To all whom it may concern:

Be it known that I, JAMES N. BROWN, a citizen of the United States, and a resident of Des Moines, in the county of Polk and

5 State of Iowa, have invented a certain new and useful Latch, of which the following is a specification.

The object of my invention is to provide a latch for doors and the like and particularly screen doors of very simple and inexpensive construction.

More particularly, it is my object to provide a latch having members adapted to be mounted respectively upon a fixed support 15 and a screen door and of such construction that when the closure member is swung to one position of its movement, the latch members will coactingly engage for holding the closure member in its position then assumed.

20 A further object is to provide in connection with said latch a locking or holding member mounted in a peculiar manner upon one of the latch elements.

With these and other objects in view, my 25 invention consists in the construction, arrangement and combination of the various parts of my device, whereby the objects contemplated are attained, as hereinafter more fully set forth, pointed out in my claim, 30 and illustrated in the accompanying drawings, in which:

Figure 1 shows a horizontal, sectional view through a door jamb closure member equipped with a latch embodying my invention.

35 Figure 2 shows a detail, sectional view taken on the line 2-2 of Figure 1.

Figure 3 shows a horizontal, sectional view taken on the line 3-3 of Figure 1.

40 Figure 4 shows a plan view of the pattern of one of the latch members.

Figure 5 shows a plan view of the pattern of the pivoted locking member; and

45 Figure 6 shows a detail, sectional, perspective view taken on the line 6-6 of Figure 2.

In the accompanying drawings, I have used the reference numeral 10 to indicate generally a door jamb adjacent to which is the free edge of the screen door or the like 11.

50 My improved latch is made of two members. One of the members for instance, the one mounted on the door 11, comprises a single piece of sheet metal folded over

on itself to form a tubular portion 12, from which extend the parallel portions 13, which terminate in oppositely extending flanges 14, which are designed to be secured to the door 11 by means of screws or the like 15.

The other latch member is made of a single piece of sheet metal.

In Figure 4, I have shown a plan of the pattern for the second latch member. The 65 pattern consists of a strip A, as shown. The strip A is folded on its transverse medial line B, forming two portions 16 parallel with and superimposed upon each other, as shown particularly in Figure 2. The pattern has slightly spaced ears 17 on opposite sides of the line B, which when the latch is formed, are bent in opposite directions from the members 16 to form flanges, as shown in Figures 1 and 2, which may be secured to the door jamb 10 by means of screws 18.

Near the free ends of the members 16, said members are curved to form spaced inwardly opening channel-shaped members 19, terminating in tongues 20, which are inclined outwardly and away from each other, as shown in Figure 2. The members 20 and 19 are designed to receive between them the portion 12 of the first latch member.

The latch members 16 are preferably made of suitable resilient material and may be riveted together near the members 19, as by the rivet 21.

In Figure 4, the holes for said rivet are 90 shown at 22 and 23. The latch members 16 are provided near the line B with holes 24 and 25, which register when the strip A is folded over to its position shown in Figure 2.

The members 16 are provided at points equi-distant from the line B with openings 26 and 27.

I provide a locking member, the pattern for which is shown in Figure 5, comprising 100 a strip C. The strip C in completing the locking member is folded over along its transverse medial line D. The strip C then forms two parallel superimposed members 28.

On one edge of the strip C at opposite ends thereof are formed ears 29, which when the members 28 are folded over on each other, are spaced apart slightly, so as to receive between them the members 16. The 110

ears 29 are provided with openings 30, which are arranged to register with the openings 22 and 23, so that a rivet or the like 31 may be inserted through the openings 30, 22 and 23.

Spaced from one of the ears 29, there is connected with one of the members 28, a tongue or projection 32, which when the locking member is mounted on the latch member by means of the rivet 31, has an end 33 bent downwardly and received in the openings 26 and 27.

Adjacent to the medial line D, the strip 28 is formed with a projecting portion 34, which is V-shaped as at 35, at its outer end.

The members 28 and the opposite sides of the member 34 are spread apart slightly, when the members 28 are folded over on each other, so as to leave a tubular member E, having the bevelled end F, as shown for instance in Figure 6.

The parts are so arranged that the downwardly-turned member 33 travels in the openings 26 and 27 and limits the swinging movement of the locking member, so that in one position of said locking member, it stands, as illustrated in dotted lines in Figure 1, with the projecting end of the member E adjacent to the opening between the portions 19. In another of its positions, the locking member stands with the member E projected between the members 19 and into the portion 12, when such portion 12 is received between the members 19, as illustrated for instance in Figure 6.

It will be seen that when my improved latch structure is mounted on the door jamb and the screen, the screen may be swung to closed position, whereupon the member 12 will enter between the members 20 and the members 19 and will be then held by the resiliency of the members 20 in such position.

If the member E should be in locking position when the member 12 enters between the members 19, the member 12 will engage the bevelled edge F and force the locking member from its full line position shown in Figure 1 to its dotted line position. Thereafter, if desired, the locking member may

be moved manually from its dotted line position illustrated in Figure 1 to its full line position in such figure.

It will be seen that my improved latch is of extremely simple and inexpensive construction. It can be made of readily available material with relatively few processes of manufacture.

It can be packed and stored in small spaces.

It is obvious that the parts may be readily adapted for fastening the door in closed position, or that by fastening one latch to the back of a door and the other to a wall or the like, the latch device may be used for holding the door in open position.

Some changes may be made in the construction and arrangement of the various parts of my improved latch device without departing from the real spirit and purpose of my invention, and it is my intention to cover by my claims, any modified forms of structure or use of mechanical equivalents, which may be reasonably included within their scope.

I claim as my invention:

In a door latch structure, a latch member comprising a strip of resilient material folded over on itself and having in its parallel portions elongated registering openings, said portions forming near one end spaced engaging members curved toward each other and then from each other at their free ends, a coacting member having an enlarged hollow end adapted to be received between said engaging members, a locking element, a means arranged to pivot one end of the locking element to said first latch member and securing together the portions of the first latch member, a member on said locking element overlapping said first latch member having a portion projecting in to said elongated openings for limiting the pivotal movement of the locking member, and means on the locking member for entering said hollow end for locking the latch members together.

Des Moines, Iowa, April 9, 1921.

JAMES NEULIN BROWN.
